CLAIM

The ornamental design for a mobile energy storage power unit, as shown and described.

DESCRIPTION

FIG. 1 is a first perspective view of a mobile energy storage power unit of the present invention;

FIG. 2 is a second perspective view of the mobile energy storage power unit;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a left side view thereof, shown in a state of use;

FIG. 10 is a right side view thereof, shown in a state of use;

FIG. 11 is an enlarged view of part I of FIG. 1; and,

FIG. 12 is an enlarged view of part II of FIG. 2.

The broken lines in the figures depict portions of the mobile energy storage power unit that form no part of the claimed design.
